PIPE AND TUBE BENDER

John D. Benfield, 755 Lakeshore Road, Grosse Pointe Shores, Mich. 48236, and Richard R. Kozinski, 4120 Kevin Road NW., North Canton, Ohio 44720

Filed Sept. 24, 1971, Ser. No. 183,719

Term of patent 14 years

Int. Cl. D8—05

U.S. Cl. D8—32

FIG. 1 is a front view of the pipe and tube bender embodying our novel design.

FIG. 2 is a back view thereof.

FIG. 3 is a view of one end thereof.

FIG. 4 is a top view thereof.

FIG. 5 is a view of the other end thereof.

FIG. 6 is a bottom view thereof.

What we claim is:

The ornamental design of a pipe and tube bender, as shown and described.
